United States Patent Office

Des. 189,121
Patented Nov. 1, 1960

189,121

SHOWER CAP OR THE LIKE

Theresa A. MacWilliams, 1821 San Marco Blvd.,
Jacksonville, Fla.

Filed July 29, 1957, Ser. No. 47,135

Term of patent 14 years

(Cl. D3—13)

Fig. 1.

Fig. 2.

Fig. 1 is a front perspective view of a shower cap embodying my new design; and

Fig. 2 is a rear elevational view, thereof.

I claim:

The ornamental design for a shower cap, or the like, as shown.
